PAPER MACHINERY

Joseph Baxter, Jr., Franklin, Ohio, assignor to The Black-Clawson Company, Hamilton, Ohio, a corporation of Ohio

Application May 22, 1956, Serial No. 586,402

13 Claims. (Cl. 92—27)

This invention relates to a rotary refiner of the Jordan type commonly used for refining of paper making stock and embodying a rotating conical plug in a complementary shell.

The invention has a primary objective the provision of a refiner of this type which will offer major practical advantages of simplicity of construction, ease of assembly and maintenance, convenience of installation, and substantial suppression of the noise of operation.

One of the specific objects of the invention is to provide a refiner of the above type wherein the main shell body is equipped at each end with a removable cover and wherein both the inlet and outlet ports are constructed in the main body itself so that one or both of the end covers may be removed for access to the interior of the body without disconnecting the piping leading to and from the interior of the body.

An additional object is to provide a refiner as outlined in the preceding paragraph wherein the end cover adjacent the larger end of the plug is secured to the main body by a quickly detachable connection for ease of removal whenever it is desired to change the filling and wherein also this quickly detachable connection incorporates a simple and effective sealing mechanism assuring maintained sealing during operation of the refiner.

Another object of the invention is to provide a refiner of the above type which is equipped adjacent each end thereof with a pair of inlet and outlet ports on opposite sides thereof for selective connection with the piping leading to and from the refiner and especially to provide such a refiner wherein the inlet port which is not connected with the piping will function as a trap for the accumulation of tramp metal and other hard trash material to prevent such material from entering between the refining surfaces of the plug and shell.

A further object of the invention is to provide a refiner of the above type wherein the conical shell portion of the main body is formed primarily by a wall located within the body and spaced inwardly from the outer wall of the main body in such manner as to define therewith a dead air space for muffling the noises created within the shell during operation of the refiner.

It is also an object of the invention to provide a rotary refiner of the Jordan type which includes end stands for the plug shaft of novel construction facilitating lubrication of the bearings for the shaft, and especially to provide such an end stand adjacent the larger end of the plug which is constructed for ready release and bodily movement with respect to the main refiner body to withdraw the plug for maintenance work on the plug or shell fillings.

Still further objects and advantages of the invention will be apparent from the following description, the accompanying drawings and the appended claims.

In the drawings:

Fig. 1 is a view in side elevation showing a rotary refiner constructed in accordance with the invention;

Fig. 2 is a plan view of the refiner of Fig. 1;

2

Fig. 3 is an enlarged view in vertical section through the refiner of Figs. 1 and 2 as indicated by the line 3—3 of Fig. 2;

Figs. 4 and 5 are enlarged fragments of Fig. 3 illustrating details of the connections between the end covers and the main body of the refiner;

Fig. 6 is a section through the main body of the refiner taken on the line 6—6 of Fig. 3 and on a smaller scale;

Fig. 7 is a fragmentary section on the line 7—7 of Fig. 6;

Fig. 8 is a fragmentary end view of the refiner looking from right to left in Figs. 1—3 and illustrating the quickly detachable connection between the main body and the end cover adjacent the larger end of the plug;

Fig. 9 is a view taken generally as indicated by the line 9—9 of Fig. 1 and showing the refiner equipped with a trap for heavy reject material;

Fig. 10 is an enlarged view partly in side elevation and partly broken away showing features of the end stand adjacent the larger end of the plug;

Fig. 11 is a fragmentary section on the line 11—11 of Fig. 10; and

Fig. 12 is an enlarged detail section on the line 12—12 of Fig. 11.

Referring to the drawings, which illustrate a preferred embodiment of the invention, the main body of the refiner is indicated generally at 10, and it includes therewithin the frustoconical shell portion 11 within which the frustoconical plug 12 is mounted for rotation by means of the shaft 13. This shaft extends outwardly from both ends of the refiner and is supported by means of separate end stands and bearing assemblies 14 and 15 shown as having a common base 16. One end of the shaft 13 is connected as by means of a coupling 17 to the drive shaft of a motor 18. The other end of the shaft is provided with an adjusting mechanism indicated generally at 20 for adjusting the axial position of the plug within the shell to control the relative spacing between the plug and shell bars 21 and 22, a suitable such adjusting mechanism being disclosed in Staegle et al. Patent No. 2,666,368 issued January 19, 1954 to the assignee of this application.

The main body 10 is shown in detail in Figs. 3 and 6, and it includes an outer wall composed primarily of a semi-cylindrical upper portion 25 and a pair of side portions 26 and 27 extending tangentially downwardly from the upper wall portion 25 and terminating in longitudinally extending flanges 28 which may be bored and tapped as shown in Fig. 6 for attachment by bolts 29 to the base 16. At each end, however, the main body is formed with cylindrical annular flange portions 30 and 31 adjacent the smaller and larger ends of the shell 11 respectively and coaxial therewith. Below each of the cylindrical flanges 30 and 31 is a web 32 and 33 respectively, and these webs extend across the end of the body and are shown as provided on the under edges thereof with keyways 34 for receiving locating keys 35 on the base 16.

The ends of the main body 10 are provided with covers 40 and 41 which are secured to the flanges 30 and 31 respectively and cooperate therewith to define an inlet chamber 44 adjacent the small end of the shell and an outlet or discharge chamber 45 adjacent the larger end of the shell. These end covers are shown as essentially dome-shaped and may be readily formed of initially identical configuration by spinning from stainless steel or other suitable corrosion resistant metal. The junction between the inlet end cover 40 and the shaft 13 is provided with a packing box 46 shown as of the water cooled type and secured to the inner periphery of the cover 40 by a bolted clamp ring 47. The junction between the outlet end cover 41 and shaft 13 is similarly provided with a packing box 48 and clamp ring connection 47. The shaft 13 is equipped with bearing sleeves

49 in the portions thereof extending through each of the packing boxes.

The connection between the inlet end cover 40 and the main body is shown in enlarged detail in Fig. 4. The cover 40 is provided with a circumferential flange 50 which seats on the flange 30 and is secured thereto by multiple bolts 51, and the flange 50 is set back from the end of the cover 40 to provide a projecting portion of the cover which extends within the flange 30. The junction of these parts is effectively sealed with relatively low clamping pressure by an O-ring 52 which is compressed against a chamfered portion 53 along the inner edge of the flange 30, and the cover 40 is therefore readily removable upon release of the bolts 51 to provide access to the inlet end of the body. This is especially advantageous in making it readily possible to remove and replace the wear ring 55 which is mounted on the smaller end of the shell and is subject to the abrasive action of the stock entering between the refining surfaces of the plug and shell. The small end of the plug carries an agitator ring 56 which is also accessible when the cover 40 is removed as well as when the plug is withdrawn from the shell.

The outlet end cover 41 adjacent the larger end of the shell is provided with a quickly releasable sealed connection to the main body in order to facilitate removal thereof whenever it is necessary to change the filling of the plug or shell. Referring particularly to Figs. 3 and 5, the end flange 31 on the body is formed with a circumferential groove 59 which receives one of the internal flanges on a split locking ring 60 of generally channeled cross section, and the ends of this ring 60 are flanged and bolted together as indicated at 61. The end cover 41 is provided with a circumferential flange ring 62 which is adapted to fit against the end face of the flange 31 on the body, but the outer peripheral portion of the flange 62 is notched at spaced intervals to provide a plurality of circumferentially spaced lugs 63 which are adapted to fit a corresponding series of notches 64 in the front flange portion of the locking ring 60.

In assembling these parts, the lugs 63 are aligned with and slipped through the notches 64 in the ring 60 to seat the flange 62 on the flange 31 on the body. The locking ring 60 may then be rotated to bring the lug portions 65 of its front flange into overlapping relation with the lugs 63 to hold the latter in place. Firmly effective interlocking of these lugs is assured by the provision of complementary wedge portions 66 and 67 on their mating surfaces as shown in Fig. 5, and the junction of these parts is sealed similarly to the other end of the body by means of an O-ring 68 on a chamfered seat 69 on flange 31.

The shell 11 is formed integrally with the outer walls of the body 10 and is supported in inwardly spaced relation therewith by means of web portions 70 and 71 adjacent the opposite ends of the body. Each of these web portions 70 and 71 is formed of generally volute shape such that each defines a pair of volute passages extending in both directions from the bottom of the body to the top thereof and leading at the top of the body into the adjacent end chamber 44 or 45 respectively. The webs 70 and 71 thus completely surround the shell 11 adjacent the opposite ends thereof and cooperate therewith and with the outer wall portions 25-27 and the base 16 to form a totally enclosed dead air space 72 surrounding the shell.

The portion of the web 70 in the lower part of the body extends tangentially out to the walls 26 and 27 and is provided with ports 75 and 76 which thus form inlet ports to the inlet chamber 44 for selective connection to an inlet conduit 77, the walls 26 and 27 being provided with bored and tapped boss portions surrounding each of these ports as shown in Fig. 6 for receiving a conventional pipe flange. The stock entering through either of these ports will therefore tend to flow tangen-

tially across the bottom of the web and then upwardly along the volute passage formed by the web 70 into the upper part of the inlet chamber 44, from whence it will be supplied to the smaller end of the shell 11 around the entire circumference thereof. Either of the ports 75 and 76 may be used to suit the convenience of the mill layout, and the unused port will be provided with a closure such as the door 78.

The web 71 is similar in configuration to the web 70 and similarly defines a pair of volute passageways connecting the discharge chamber 45 with a pair of ports 80 and 81 on opposite sides of the main body for selective attachment to the outlet conduit 82 as shown in Fig. 2, this port arrangement being identical with that of the ports 75 and 76. The stock entering the outlet chamber from between the working surfaces of the plug and shell will therefore be conducted to the selected outlet port by the volute passageway with minimum hydraulic losses for efficient operation. As in the case of the inlet ports, the selection of the outlet port to be used depends on convenience, and the unused port will be provided with a closure 83 which may be identical with the door 78.

This refiner construction provides a variety of important practical advantages. Thus as already noted, the piping leading to and from the refiner may be arranged on either side of the main body to suit the convenience of the mill, and the location of the inlet and outlet ports close to the bottom of the body offers a further distinct advantage in facilitating anchoring of the pipes to the floor close to the body in order to dampen the transmission of vibrations. Another significant contribution to quiet operation is made by the construction of the body to provide the dead air space 72 surrounding the shell, which effectively absorbs and suppresses a substantial amount of the noise and vibrations created by the normal operation of the refiner.

The end cover arrangement for the main body offers further practical advantages as well as economy of production. For example, with the covers of spun construction as described, both the inlet and outlet chambers will drain completely to the adjacent ports whenever it is desired to shut down the machine, and also there will be minimum tendency for deposit of fibers on the walls of either chamber. In addition, since the ports are cast in the main body, either or both of the end covers can be removed without in any way interfering with the piping connections, and the quickly detachable connection between the outlet end cover 41 and the body is a further aid in the reduction of down time whenever it is necessary to change or otherwise to service the fillings.

A still further important practical advantage is obtained from the arrangement of a pair of selectively usable ports at each end of the body, and particularly at the inlet end. Thus by reference to Fig. 6, it will be apparent that stock entering through the port 75 will first flow tangentially across the bottom of the body before it turns upwardly along the volute passage formed by the web 70. Both gravity and the flow pattern of this entering stock will therefore tend to throw tramp metal or other reject material towards the unused port 76, and the space within the body adjacent this port will tend to act as a trap for such reject material. It will therefore be a simple matter to remove such reject material periodically by shutting off the incoming flow to the refiner and then opening the closure door 78 to take out the accumulated trash. The unused ports may also be employed to advantage for flushing out the interior of the refiner by means of steam or fresh water without interfering with the main piping connections for the stock.

Fig. 9 illustrates further means for utilizing one of the ports at the inlet end of the body for reject trapping purposes. In Fig. 9, the inlet pipe 77 is connected as in Figs. 1 and 2 to the port 75, but the port 76 is con-

nected to a trap unit comprising an elbow 90, a first valve 91, a pipe section 92, a second valve 93 and a discharge pipe 95. In normal operation, the valve 91 will be open and the valve 93 will be closed, and heavy reject material will therefore be thrown through the elbow 90 into the pipe section 92. At intervals, this reject material is removed by shutting valve 91 and then opening valve 93, and this may be done without interference with the normal flow of stock through the refiner. Improved operation is obtained by bleeding a small flow of water into the pipe section 92 just above the valve 93, as shown in Fig. 9 by the line 96 having a control valve 97.

Figs. 10-12 illustrate details of the end stand 15 for the larger end of the plug which facilitates maintenance of the refiner. During operation of the unit, the pedestal 100 is rigidly secured to the base 16 by screws 101, but provision is made upon release of these screws for moving this entire assembly bodily along base 16 to the extent necessary to withdraw the plug 12 from the body for service of their respective fillings. For this purpose, the base 16 is equipped with extension means 102 such as rails secured thereto as shown in Fig. 10.

The movement of the end stand 15 is effected by means of a pair of shafts 105 and 106 extending across the bottom of the pedestal 100 and journaled in bushings 107. Each of these shafts includes an eccentric portion 110 near each end thereof, and a ball bearing 111 is journaled on each of these eccentrics and is held in place thereon by a collar 112 or stop arm 115. Each shaft is also provided at one or both ends with a noncircular portion 116 for receiving a crank or other operating lever.

With this construction, when the refiner is in operation, the shafts 105 and 106 are turned to the positions shown in Figs. 10-12 in which the bearings 111 are out of contact with the base 16, and the pedestal 100 is screwed directly to the base. When the plug is to be withdrawn from the body, the screws 101 are removed, and the shafts 105 and 106 are rotated to shift the eccentrics thereon downwardly until the bearings 109 engage the track portions 120 of the base and then raise the pedestal free of the base. The stop arms 115 engage the adjacent flange portions 121 and 122 of the pedestal to index the shafts in the desired adjusted position—in which the eccentrics 110 have moved just past lower dead center—and then the entire unit 15 can be rolled along the base 16 and extension 102 by means of bearings 110 to the desired extent.

Fig. 10 also illustrates the convenient provisions in the pedestal 100 for lubricating the bearing assembly for the plug shaft 13. The housing 125 contains a lubricating assembly, including a pump and drive motor, for providing a circulating oil supply to the bearing assembly by way of the oil lines 126 and 127. The housing 125 may be exchanged as a unit without interfering with operation of the refiner, by simply uncoupling the oil lines, and a similar lubricating assembly is provided in the end stand 14, as indicated by the oil line 128 in Fig. 1.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A rotary refiner of the character described for liquid slurry stock comprising a main body having coaxial annular end portions, a frustoconical shell within and integral with said main body and of substantially smaller diameter at both ends than the adjacent end portion of said main body, a cover secured to each of said end portions of said main body in overlying relation with

the adjacent end of said shell and cooperating therewith to define end chambers for stock adjacent each end of said shell, means forming part of said main body and adjacent each end thereof defining a port connecting with the adjacent said end chamber, means for connecting inlet and outlet conduits for stock to said ports adjacent the smaller and larger ends of said shell respectively, a frustoconical plug substantially complementary to said shell, means including a shaft extending through said covers and mounted externally thereof for supporting said plug for rotation within said shell, and means forming seals at the junctions between said shaft and said covers.

2. A rotary refiner of the character described for liquid slurry stock comprising a main body including an outer wall having coaxial annular end portions, a frustoconical shell within and integral with said main body and of substantially smaller diameter at both ends than the adjacent end portion of said main body, integral web means supporting said shell within said body and cooperating with both thereof to form an enclosed space between said shell and said outer wall of said body for muffling sound from within said shell, a cover secured to each of said end portion of said main body in overlying relation with the adjacent end of said shell and cooperating therewith to define end chambers for stock adjacent each end of said shell, means forming part of said main body and adjacent each end thereof defining a port connecting with the adjacent said end chamber, means for connecting inlet and outlet conduits for stock to said ports adjacent the smaller and larger ends of said shell respectively, a frustoconical plug substantially complementary to said shell, means including a shaft extending through said covers and mounted externally thereof for supporting said plug for rotation within said shell, and means forming seals at the junctions between said shaft and said covers.

3. A rotary refiner of the character described for liquid slurry stock comprising a main body having coaxial cylindrical end portions, a frustoconical shell within and integral with said main body and of substantially smaller diameter at both ends than said end portions of said shell, a generally dome-shaped cover secured to each of said end portions of said body in overlying relation with the adjacent end of said shell and cooperating therewith to define end chambers for stock adjacent each end of said shell, means forming part of said main body and adjacent each end thereof defining a port connecting with the adjacent said end chamber, means for connecting inlet and outlet conduits for stock to said ports adjacent the smaller and larger ends of said shell respectively, a frustoconical plug substantially complementary to said shell, means including a shaft extending through said covers and mounted externally thereof for supporting said plug for rotation within said shell, and means forming seals at the junctions between said shaft and said covers.

4. A rotary refiner of the character described for liquid slurry stock comprising a main body including an outer wall having coaxial annular end portions, a frustoconical shell within and integral with said main body and of substantially smaller diameter at both ends than the adjacent end portion of said main body, a cover secured to each of said end portions of said main body in overlying relation with the adjacent end of said shell and cooperating therewith to define end chambers for stock adjacent each end of said shell, said main body including at each end thereof a portion defining a generally volute passage connecting at one end with the adjacent said end chamber and having a port at the other end thereof extending through said wall of said body, means for connecting inlet and outlet conduits for stock to said ports adjacent the smaller and larger ends of said body respectively, a frustoconical plug substantially complementary to said shell, and means including a shaft extending

through said covers and mounted externally thereof for supporting said plug for rotation within said shell.

5. A rotary refiner of the character described for liquid slurry stock comprising a main body having coaxial annular end portions, a frustoconical shell within and integral with said main body and of substantially smaller diameter at both ends than the adjacent end portion of said main body, a cover secured to each of said end portions of said main body in overlying relation with the adjacent end of said shell and cooperating therewith to define end chambers for stock adjacent each end of said shell, said main body including at each end thereof a portion defining a pair of generally volute passages extending in both directions from the bottom of said body to the top thereof and leading at the top of said body into the adjacent said end chamber, means defining a pair of ports on each side of said body and adjacent the bottom thereof connecting substantially tangentially into the adjacent said volute passages, means for connecting inlet and outlet conduits for stock to a selected one of each of said pair of ports adjacent the smaller and larger end of said shell respectively, closure means for blocking the others of said ports, a frustoconical plug substantially complementary to said shell, and means including a shaft extending through said covers and mounted externally thereof for supporting said plug for rotation within said shell.

6. A rotary refiner of the character described for liquid slurry stock comprising a main body having coaxial cylindrical end portions, a frustoconical shell within and integral with said main body and of substantially smaller diameter at both ends than said end portions of said shell, integral web means supporting said shell within said body and cooperating with both thereof to form an enclosed space between said shell and said outer wall of said body for muffling sound from within said shell, a cover secured to each of said end portions of said main body in overlying relation with the adjacent end of said shell and cooperating therewith to define end chambers for stock adjacent each end of said shell, means forming part of said main body and adjacent each end thereof defining a port connecting with the adjacent said end chamber, means for connecting inlet and outlet conduits for stock to said ports adjacent the smaller and larger ends of said shell respectively, a frustoconical plug substantially complementary to said shell, and means including a shaft extending through said covers and mounted externally thereof for supporting said plug for rotation within said shell.

7. A rotary refiner of the character described for liquid slurry stock comprising a main body having coaxial cylindrical end portions, a frustoconical shell within and integral with said main body and of substantially smaller diameter at both ends than said end portions of said shell, integral web means supporting said shell within said body and cooperating with both thereof to form an enclosed space between said shell and said outer wall of said body for muffling sound from within said shell, a cover secured to each of said end portions of said main body in overlying relation with the adjacent end of said shell and cooperating therewith to define end chambers for stock adjacent each end of said shell, said main body including at each end thereof a portion defining a pair of generally volute passages extending in both directions from the bottom of said body to the top thereof and leading at the top of said body into the adjacent said end chamber, means defining a pair of ports on each side of said body and adjacent the bottom thereof connecting substantially tangentially into the adjacent said volute passages, means for connecting inlet and outlet conduits for stock to a selected one of each of said pair of ports adjacent the smaller and larger end of said shell respectively, closure means for blocking the others of said ports, a frustoconical plug substantially complementary to said shell, and means including a shaft extending through said

covers and mounted externally thereof for supporting said plug for rotation within said shell.

8. A rotary refiner of the character described for liquid slurry stock comprising a main body including an outer wall having coaxial annular end portions, a frustoconical shell within and integral with said main body and of substantially smaller diameter at both ends than the adjacent end portion of said main body, a pair of covers each proportioned to fit one of said end portions of said main body in overlying relation with the adjacent end of said shell and cooperating therewith to define end chambers for stock adjacent each end of said shell, means defining a pair of ports extending through said outer wall of said body and connecting with said end chambers respectively, connecting means for connecting inlet and outlet conduits for stock to said ports adjacent the smaller and larger ends of said shell respectively, a frustoconical plug substantially complementary to said shell, means including a shaft extending through said covers and mounted externally thereof for supporting said plug for rotation within said shell, and releasable means for securing said covers directly to said body to provide for selective release and withdrawal of said covers from said body for access to the adjacent said end chamber without disconnecting said conduit connecting means.

9. A rotary refiner of the character described for liquid slurry stock comprising a main body including an outer wall having coaxial cylindrical end portions, a frustoconical shell within and integral with said main body and of substantially smaller diameter at both ends than the adjacent end portion of said main body, a pair of covers each proportioned to fit one of said end portions of said main body in overlying relation with the adjacent end of said shell and cooperating therewith to define end chambers for stock adjacent each end of said shell, means defining a pair of ports extending through said outer wall of said body and connecting with said end chambers respectively, connecting means for connecting inlet and outlet conduits for stock to said ports adjacent the smaller and larger ends of said shell respectively, a frustoconical plug substantially complementary to said shell, means including a shaft extending through said covers and mounted externally thereof for supporting said plug for rotation within said shell, and releasable means for securing said covers directly to said body to provide for selective release and withdrawal of said covers from said body for access to the adjacent said end chamber without disconnecting said conduit connecting means, said releasable means adjacent said larger end of said shell including a locking ring mounted for rotational movement on said body between locking and release positions with respect to the adjacent said cover to facilitate quick removal of said cover.

10. A rotary refiner of the character described for liquid slurry stock comprising a main body including an outer wall having coaxial annular end portions, a frustoconical shell within and integral with said main body and of substantially smaller diameter at both ends than the adjacent end portion of said main body, a pair of covers each proportioned to fit one of said end portions of said main body in overlying relation with the adjacent end of said shell and cooperating therewith to define end chambers for stock adjacent each end of said shell, means defining a pair of ports extending through said outer wall of said body and connecting with said end chambers respectively, connecting means for connecting inlet and outlet conduits for stock to said ports adjacent the smaller and larger ends of said shell respectively, a frustoconical plug substantially complementary to said shell, means including a shaft extending through said covers and mounted externally thereof for supporting said plug for rotation within said shell, a wear ring removably secured to the smaller end of said shell and accessible for replacement upon removal of the adjacent said cover, and releasable means for securing said covers directly to said

body to provide for selective release and withdrawal of said covers from said body for access to the adjacent said end chamber without disconnecting said conduit connecting means.

11. A rotary refiner of the character described for liquid slurry stock comprising a main body having coaxial annular end portions, a frustoconical shell within and integral with said main body and of substantially smaller diameter at both ends than the adjacent end portion of said main body, a cover secured to each of said end portions of said main body in overlying relation with the adjacent end of said shell and cooperating therewith to define end chambers for stock adjacent each end of said shell, means forming part of said main body and adjacent each end thereof defining a port connecting with the adjacent said end chamber, means for connecting inlet and outlet conduits for stock to said ports adjacent the smaller and larger ends of said shell respectively, a frustoconical plug substantially complementary to said shell, a shaft extending through said covers and supporting said plug for rotation within said shell, a base, means securing said body to said base, end stands including bearings for rotatably supporting said shaft on said base, releasable means for securing to said base the said end stand adjacent the larger end of said plug, and means carried by said releasably secured end stand for raising said end stand with respect to said base upon release of said releasable means and for effecting free movement of said end stand along said base to withdraw said plug from within said shell.

12. A rotary refiner as defined in claim 11 wherein said last named means comprises shaft means carried by said end stand and having eccentric portions thereon, anti-friction rollers on said eccentric shaft portions,

5 and means journaling said shaft means in said end stand in predetermined spaced relation with said base providing for rotation of said shaft means between a position retaining said rollers raised out of contact with said base and a position wherein said rollers engage said base and support said end stand out of contact with said base for rolling movement therealong on said rollers.

10 13. In a rotary refiner including a conical plug supported on a shaft extending through a main body mounted on a base, the combination of an end stand for supporting the end of said shaft adjacent the larger end of said plug, releasable means for securing said end stand to said base, shaft means journaled in said end stand and having eccentric portions thereon, anti-friction rollers on 15 said eccentric shaft portions and rotating with said shaft means to a raised position out of contact with said base, and means establishing limit positions for said shaft means sufficiently beyond the lower dead center positions for said eccentric portions thereof to effect raising of said end stand out of contact with said base by said rollers for rotation along said base on said rollers.
